SWITCH MECHANISM FOR AUTOMOBILE CLOCKS

Fred R. Schweigler, Delavan, Wis., assignor to
The George W. Borg Corporation, Chicago, Ill.,
a corporation of Delaware

Application May 28, 1949, Serial No. 95,959

2 Claims. (Cl. 200—67)

1

The present invention relates in general to automobile clocks, but more in particular to spring driven automobile clocks which are provided with automatic electromagnetically operated winding mechanisms; and the object of the invention is a new and improved switch for controlling the circuit of the winding electromagnet in a clock of this character.

An automobile clock of the general type with which the invention is concerned is disclosed in the patent to Hobbs, No. 2,146,119, granted February 7, 1939. As shown in the drawing, however, the invention is applied to an improved form of clock, disclosed in the pending application of Olson, Serial No. 710,983, filed November 20, 1946, in which the winding mechanism is in the form of a detachable unit which is interchangeable with other winding mechanisms.

The switch which forms the subject matter of the invention is a toggle type of switch, adapted to open and close with a snap action, and is characterized by the feature that the power for opening the switch is transmitted through the switch contacts, which insures that the contacts will remain closed with ample contact pressure until the movable arm of the toggle mechanism passes through its dead center position.

The invention and other features thereof are described more in detail in the specification which follows, reference being had to the accompanying drawing.

In the drawing, Fig. 1 is a top or plan view of a clock winding mechanism having a switch constructed in accordance with the invention, the switch being shown in open position; Fig. 2 is a partial view of the winding mechanism of Fig. 1, with the switch in closed position; and Fig. 3 is a side view of the winding mechanism and switch, with the latter in open position as it appears in Fig. 1.

Referring to the drawing, the various parts of the winding mechanism, also sometimes referred to as the motor mechanism, are mounted on a frame which comprises the circular back plate 10 and T-shaped armature bearing plate 11. These plates are held together in spaced relation by three pillars 12, 13, and 14, as indicated in Figs. 1 and 3.

The electromagnet has a winding 15, a core 16 and two pole pieces 17 and 18. The pole pieces may be stamped from sheet stock and are assembled on the core as shown in Fig. 1. The electromagnet is mounted on the back plate 10. For this purpose the pole pieces 17 and 18 are provided with integrally formed studs such as 19, Fig. 3, which extend through holes in the back plate.

The ends of these studs are staked or riveted to hold the electromagnet in place.

The armature is indicated by reference numeral 20 and is rotatably mounted on the bearing plate 11 by means of the hollow shoulder stud 21 and the bushing 22. The main spring is indicated at 23 and tends to rotate the armature 20 in a clockwise direction. During such rotation the pawls 25 and 26 engage a ratchet wheel (not shown) which is part of the clock movement and the spring 23 thus furnishes power for driving the clock. The arrangement is shown in detail in the Hobbs patent and also in the application of Olson previously referred to.

The armature is shown in wound or partly wound position in Fig. 1. As it is rotated slowly by spring 23 to drive the clock, the spring gradually loses its tension but before this has proceeded too far the switch to be described hereinafter is operated by the pin 24 carried on the armature 20, and the electromagnet 15 is energized. The armature is then quickly rotated in a counterclockwise direction to its fully wound position. During this movement of the armature, the switch is opened to deenergize the electromagnet and the main spring is retensioned, so that it can resume its function of supplying power to drive the clock. The clock movement includes known means for maintaining power during winding, that is, during the rotation of the armature to wound position.

The various parts of the switch are mounted on a bracket 30, which may be a stamped and formed part made from heavy sheet brass. The bracket is attached to the back plate 10 by means of two spacers 31 and 32, which are in the form of shoulder studs riveted to the bracket. The screws 33 and 34 pass through holes in the back plate and are threaded into the shoulder studs. One or both of these holes may be made somewhat oversize to provide for adjusting the position of the bracket.

The switch includes a contact arm or lever 38, which is pivotally mounted on the bracket 30 by means of a shoulder screw 41 and an insulated stud which has the head 35 and shank 36. The shank 36 passes through the bracket and a washer 37, also the two discs of insulating material which are shown on opposite sides of the bracket, and the end is upset by riveting to hold the stud in place. The shoulder screw 41 passes through the lever 38 and is threaded into the stud. The lever 38 has the contact 55 at one end and at the other end has an upwardly extending part 56 carrying the tubular insulator 47.

The contact lever 38 also forms part of the

switch and is pivotally mounted on the bracket 30 by means of the stud 42 and the shoulder screw 43. The stud is riveted to the bracket, while the shoulder screw passes through the lever and is threaded into the stud. The lever 39 has a contact 54 at one end adapted to cooperate with the contact 55 on lever 38. At the other end, lever 39 has an arm 57 which is engaged by insulator 47 when the switch is in open position, as shown in Fig. 1.

The lever 39 is rotated on its pivot by the pin 24 previously referred to, which is fixed to the armature 20 and extends down between the two fingers of the fork 58 which forms part of the lever. The lever 39 has a limited movement on its pivot, due to the provision of a pin 40 which is secured to the lever and which extends downward into a slot 45 in the bracket 30. The slot has the proper length to permit the required movement of the lever 39 and no more.

The lever 38 also has a limited movement on its pivot, the extremities of which are determined by the engagement of contact 55 with contact 54 when the switch is closed and by the engagement of insulator 47 with arm 57 when the switch is open. The lever 38 is at all times urged toward either open or closed position by the toggle mechanism of which it forms a part and which includes the spring 51 and the notched member 46. The spring 51 includes a part 50 which is provided with the soldering tab or ear 52 and is clamped to the down turned end of bracket 30 by means of the rivet 53. The spring is insulated from the bracket and rivet by the insulators shown, inserted on opposite sides of the part 50 of the spring. As seen in the several figures of the drawings, the spring 51 is tensioned to the right to bear against the end of the member 46, which is supported between the curved end of the spring and a notch in the lever 38. Thus the spring is adapted to move the lever 38 to either of its extreme positions with a snap action.

One end of the winding of the electromagnet 15 is connected to the spring clip 60 which is conductively connected to the binding post 61. This binding post is insulated from the back plate 10 and is connected to the live pole of the battery when the clock is installed in an automobile. The other end of the winding is soldered to the ear 52 on spring 50-51. When the switch is closed this end of the winding is connected to the ground binding post 62 by way of spring 50-51, member 46, lever 38, contacts 55 and 54, lever 39, bracket 30, and back plate 10. The ground binding post and the other pole of the battery may be connected through the frame of the car.

The operation of the switch will now be described more in detail. For this purpose it will be assumed that a clock movement is assembled to the motor mechanism and that the complete clock is installed and connected up as described in the foregoing.

As previously mentioned, the spring 23 drives the clock by rotating the armature 20 in a clockwise direction as seen in Fig. 1, the pawls 25 and 26 performing the driving function by their engagement with a ratchet wheel which is part of the clock movement. The motor mechanism is wound or partly wound as seen in Fig. 1. The switch is open, that is, the contacts 54 and 55 are separated, and the electromagnet 15 is deenergized. The switch is held open by the spring 51 and member 46, which tend to rotate the lever 38 in a clockwise direction. The insulator 47 therefore bears against the arm 57 of lever 39 and

tends to rotate this lever in a clockwise direction, but the lever has reached the end of its movement in this direction due to the engagement of pin 40 with the end of the slot 45.

As the armature 20 rotates under power supplied by spring 23 to drive the clock, the pin 24 approaches and shortly engages the left hand finger of the fork 58 on lever 39. Further movement of the pin 24 rotates the pivoted lever 39 in a counterclockwise direction, and lever 39, due to the engagement of insulator 47 by arm 57, rotates the pivoted lever 38 in the same direction. The rotation continues until the pin 40 has nearly reached the end of the slot 45, at which time the toggle mechanism 51-46-38 passes through dead center and the lever 38 suddenly shifts or snaps over to the position in which it appears in Fig. 2. In this position the switch is closed, that is, contact 55 is in engagement with contact 54. The lever 39 is at the end of its counterclockwise movement, determined by the engagement of pin 40 with the other end of slot 45.

When the switch is closed as described in the foregoing, the electromagnet 15 is energized and the armature 20 is quickly rotated to its Fig. 1 position, or to a position somewhat beyond, which is reached due to the inertia of the armature and to the delay in decay of the magnetization of the electromagnet. During this movement of the armature the pin 24 engages the right hand finger of the fork 58 and rotates lever 39 in a clockwise direction. Lever 39, due to the engagement of contact 54 with contact 55, rotates the lever 38 in a clockwise direction, until the toggle parts again pass through dead center, whereupon lever 38 shifts over to its Fig. 1 position with a snap action and opens the switch by separating the contacts 55 and 54. The electromagnet accordingly deenergizes, the pawls take a fresh hold on the ratchet wheel, and the drive is resumed under power supplied by the re-tensioned spring 23.

The fork 58 is so designed that when the switch snaps to open position the right hand finger clears pin 24, that is, moves out of the path of the pin, so that any further rotation of the armature that takes place cannot affect the switch.

The operation continues as described, the clock being rewound periodically by energization of the electromagnet under control of the switch. The period depends on the adjustment of the parts and other factors, but preferably is on the order of about three minutes.

An advantageous feature of the switch is the wiping action which takes place between the contacts 54 and 55 when the switch shifts from closed to open position. This tends to eliminate trouble caused by dirty or corroded contacts.

Perhaps more important, however, is the feature referred to before, according to which the power for operating the switch or, more specifically, for operating the toggle mechanism, is applied through the switch contacts. The contacts do not open, therefore, until the parts pass through dead center, and this point is passed under power with the electromagnet fully energized. The arrangement thus insures a more positive action than is possible with the Hobbs and other types of toggle switches in which the switch contacts open before dead center is reached, and which depend, for passing through dead center, on the inertia of the armature and the delayed deenergization of the electromagnet.

The invention having been described, that

which is believed to be new and for which the protection of Letters Patent is desired will be pointed out in the appended claims.

I claim:

1. In a switch mechanism, two switch members extending generally parallel to each other, means for pivotally supporting said members for rotation about different axes, the pivot for each member being located at a point intermediate the ends thereof, means for rotating the first said member on its pivot in one direction, whereby one end of said first member engages the corresponding end of the second member and rotates said second member, interposed insulating means to prevent conductive contact between the said ends of said members, a spring acting on said second member to continue the rotation thereof after it has been rotated a predetermined amount by said first member, a switch contact at the other end of said second member brought into engagement with a switch contact at the other end of said first member responsive to said continued rotation, and means for rotating said first member in the opposite direction to thereby rotate said second member by power applied through said contacts, said spring being effective thereafter to prolong the rotation of said second member to separate said contacts.

2. In a switch mechanism, two switch members extending generally parallel to each other, means for pivotally supporting said members for rotation about different axes, the pivot for each

member being located at a point intermediate the ends thereof, cooperating switch contacts carried on said members at corresponding ends thereof, an insulator carried on the other end of one said member and adapted for engagement with the corresponding end of the other member, said pivots being located far enough apart so that the second member has a limited movement on its pivot independent of the first member, means for rotating the first said member in one direction to apply force through said insulator to rotate the second member, means for rotating the first member in the other direction to apply force through said contacts to rotate said second member, and a spring acting on said second member and effective whenever the said second member is rotated by said first member to prolong the rotation of the second member to thereby break the initial engagement between said members and effect engagement between said members at the other ends thereof.

FRED R. SCHWEIGLER.
